APPARATUS FOR THE PRODUCTION OF
POWDERS OF LOW-MELTING-POINT
METALS OR OF COMPOUNDS THEREOF

Siegfried Hiller, London, England

Application January 24, 1939, Serial No. 252,678
In Great Britain September 30, 1938

5 Claims. (Cl. 83—91)

This invention relates to apparatus for the production of fine powders of low-melting-point metals or compounds thereof, in particular of metallic lead or lead oxides.

5 There is known apparatus for making lead oxide in which the lead is melted in an externally heated vessel, is atomised by being whirled against the walls of the vessel by the blades of a stirring device acting upon the surface of the lead vertically or obliquely, or by percussion devices dipping into the surface of the molten lead, and the lead is oxidised by the introduction of hot air or superheated steam or a mixture of air and steam. According to another proposal a centrifugal wheel dipping into a lead bath is formed as a fan for drawing in the current of gas necessary for conducting away the resulting lead-oxide dust, and blades secured to the centrifugal wheel fit, as closely as possible, part of the internal surface of a pear-shaped oxidation chamber inclined upwardly from the lead bath for the purpose of scraping loose lead oxide adhering to the internal surface of the oxidation chamber. In each of these known apparatus the metal-melting vessel and the atomising or oxidation chamber are built-in in such a manner that the atomising devices are very difficult of access and therefore much trouble is involved in repairing any injury to the parts in question. There is also known an apparatus for the making of lead oxide in which the lead flows from the melting vessel into a centrifugal mill, which is formed as a fan and in which the atomised lead is oxidised by means of drawn-in air, whilst the resulting product falls into a precipitating chamber. This apparatus is attended by the disadvantage that incrustation is apt to occur in the conduit through which the liquid lead passes into the centrifugal mill in the centrifugal mill itself. A further disadvantage of this apparatus is that the liberated crusts and coarser particles of unchanged metallic lead pass with the oxidation products, into the precipitating chamber and may require subsequent separation.

An object of the present invention is the provision of apparatus for the purpose above indicated, from which the centrifugal device can be easily removed for purposes such as repair or cleaning, from the melting vessel. A further object is the construction of the centrifugal device as a unit. A further object is improving the facilities for attending to and charging the melting vessel. Yet another object is the provision for the purpose indicated of a centrifugal device which receives the molten metal merely by partial immer-

sion; and in which provision exists for the return and further comminution of such metal as may be above certain grades of size after treatment, this being accomplished by simple gravitational means.

In apparatus according to the invention the centrifugal device can be easily removed and repaired or cleaned away from the furnace and the metal-melting vessel, whilst the melting furnace and the melting vessel can be used if required for other purposes after the removal of the centrifugal device. Further, the melting furnace and the melting vessel can be easily attended to and changed.

Now an apparatus for the purpose in question according to the invention, comprises an externally heated metal-melting vessel and a flinger device which is arranged so that molten metal will flow into the atomising chamber or casing of the said device through an opening or openings in the lower portion of the said chamber and be acted upon by the rotary portion of the said device; and which may be constructed as a unit and adapted to be readily removable independently of the metal-melting vessel.

Moreover the outlet portion of the peripheral wall of the atomising chamber is preferably streamlined in the direction of outward and upward travel of the metal particles for a purpose hereinafter stated. For the purpose of the sifting of the products by gravity the outlet of the centrifugal atomising chamber has connected to it a vertical upwardly extending chamber through which the light particles are carried in opposition to the action of gravity by a current of gas, whilst coarse particles drop directly into the atomising chamber, where they are further comminuted so that only the finest particles are carried by the current of gas into a connecting chamber. The material is thus completely treated so that there is no inferior product that must be removed. It is usually unnecessary to grind the resultant product even if it is to be used for the making of paint.

The invention is illustrated by the accompanying diagrammatic drawing, which represents an example of apparatus according thereto which is suitable both for the production of finely divided lead or lead dust, and also for the production of oxidation products of lead; Figure 1 is a section corresponding to the line I—I of Figure 2, and Figure 2 is a section corresponding to the line II—II of Figure 1.

In a furnace 1 there is inserted a vessel 2 in which the lead is melted. The centrifugal atom-

ising device comprises a rotary wheel 3, having radial vanes 3a, and an atomising chamber or casing 4 having a peripheral wall 4a carried by the shaft 3b of the wheel 3, which shaft is mounted in bearings 3c which are, for example, removably bolted to the wall of the furnace 1, and is driven, for example by electric motor. The shaft 3b has a coupling 3d for readily coupling the source of power; or it may have a 10 pulley for a belt, or other driving means. The wall 4a has, at the bottom thereof, openings 5 which may, as shown, be provided with short outwardly projecting tubes 5a, for the entry of molten metal from the vessel 2 into the atomising 15 chamber so that at least the vanes of the rotary portion 3 dip into and act directly upon the molten metal which has flowed thereto. The outlet portion of the peripheral wall 4a of the casing is stream-lined in the direction of outward 20 and upward travel of the metal particles, in accordance with the direction of rotation indicated by the arrow on the wheel 3, so as to facilitate the upward travel of the particles and also the falling back of the larger particles into the centrifugal device for further comminution; the remainder of the wall 4a is concentric with the wheel 3. The end walls of the casing 4 are advantageously bolted to the peripheral wall 4a so as to render the interior of the centrifugal 25 device easily accessible for repair or cleaning. In extension of the outlet of the casing, which may if desired be provided with baffles, there is connected a vertically upwardly extending chamber 6 which is intended for sifting by gravity 30 and may if desired be used for further treatment, for example oxidation, and which may be heat-insulated or heated. The cross-section of the chamber 6 in the upward direction first widens and then narrows, so that, owing to the reduction 35 of the velocity with which the suction gases transport the particles, the dropping back into the atomising device of heavy particles that have been thrown upwards by the wheel 3 of the centrifugal device is assisted and the sifting is improved. In this chamber there may be provided 40 baffles for assisting the sifting of the material. The chamber 6 ends in a delivery tube 7 which leads to an ordinary collecting vessel (not shown). If the powdered metal is to be oxidised, there is 45 introduced through a pipe 8 into a conduit 9a, 9b, heated air or steam or a mixture of air and steam or some suitable oxidising gas, for the suction of which there may serve the wheel 3 of the centrifugal device if it is, as shown, formed 50 as a fan. The conduit 9a, 9b, is composed of two parts 9a and 9b, which are connected together by a flange joint 9c so as to be easily discon- 55 nectible to enable the whole centrifugal device to be removed as a unit when necessary. The 60 part 9b serves as the mounting for securing the chamber 4 in the desired position, and preferably joins the casing 4 axially, as seen in Figure 2. The wheel 3 has any required known formation to act as a centrifugal blower, and to suck gases 65 in through the conduit 9b.

For the purpose of utilising the heat of the waste gases of the furnace that heats the metal in the vessel 2, those gases may be introduced through an outlet 10 and a conduit 11 into the 70 conduit 9a, 9b, so that the heat of those gases will serve for maintaining the desired temperature (which is usually somewhat above the melting point of the lead) in the atomising chamber and in the chamber 6 connected thereto. If desired, the waste gases may, before being intro-

duced into the atomising chamber, be freed from dust by means of a filter 15 or be otherwise purified. A valve 14 enables the supply of the waste gases to be regulated or stopped; when stopped by the valve 14 they may be allowed to escape past a valve 12, into a flue. The supply of air or steam is regulated by a valve 13.

The operation of the apparatus is as follows in the case of the production of lead oxide:

By the wheel 3 of the atomising device molten lead, of which the surface is shown at 2a, well above the lowest point to which the vanes 3a extend, is thrown against the wall 4a of the atomising chamber and the resulting particles of comminuted metal are projected into the chamber 6. The metal particles are at the same time oxidised by drawn-in hot gases or steam and the oxidation products are transported by the current of gas or steam through the chamber 6 and led away through the pipe 7, whilst the unoxidised relatively heavy metal particles drop back directly into the atomising chamber and are further comminuted therein. In this way there is obtained lead oxide in a state of very fine division, which can be used as it is for decorative or anti-rust paints or converted into red lead without further grinding or used for other purposes, for example for making masses for accumulators.

The apparatus according to the invention may be used also for the making of other finely divided lead compounds for example lead carbonate, for which carbonic acid and air are introduced into the atomising chamber.

In the case of the manufacture of finely divided metallic lead the operation is the same except that the supply of oxidising gas or steam is omitted and the carrying away of the metal powder is effected by means of non-oxidising gases, for example carbon monoxide or nitrogen, or reducing gases, as the reducing waste gases from the melting furnace.

Apparatus according to the invention may be similarly used for the obtaining in a finely divided form or other low-melting-point metals, as tin, antimony, or cadmium, and their compounds.

What I claim is:

1. In apparatus for finely comminuting molten metal in a melting vessel, a comminuting unit partially immersible in said vessel comprising a rotatable flinger wheel and a casing therefor with an inlet in the bottom thereof through which molten metal from the said vessel can enter the casing, and an outlet passage at the upper part of the casing through which finely comminuted metal is projected, the bottom part of the casing extending underneath said flinger wheel in conformity with and in close proximity to the periphery thereof.

2. Apparatus for finely comminuting molten metal comprising in combination a rotatable flinger wheel, a casing forming a comminuting unit therewith adapted to be partially immersible in a bath of molten metal in a melting vessel, an inlet in the bottom of said casing through which molten metal can flow from said vessel into said casing into contact with said flinger wheel and an outlet at the upper end of the casing through which finely comminuted metal is projected, said casing extending underneath said wheel in conformity with and in close proximity to the periphery thereof.

3. In apparatus for the production of powders of low-melting-point metallic products including a metal melting vessel, a comminuting unit

comprising in combination a rotatable flinger wheel, a casing extending underneath said wheel in conformity with and in close proximity to the periphery thereof, an inlet at the bottom of the casing, an outlet at the upper part of the casing, driving means for said flinger wheel and means for supporting said wheel and casing in a readily detachable manner relative to the melting vessel and in a partially immersed condition so that metal can flow into the casing into contact with the flinger wheel to be finely comminuted and projected thereby.

4. Apparatus for the production of powders of low-melting-point metallic products, comprising in combination a casing having an inlet in the bottom thereof, a flinger wheel rotatably mounted in a vertical plane in said casing, radial vanes on said wheel, a substantially vertical outlet duct associated with said casing, and means for mounting said wheel and casing in a readily detachable manner on a separate melting vessel

and partially immersed in molten metal therein, a part of the casing extending underneath said wheel in close proximity to said vanes so that the metal flowing into the casing through said inlet is finely comminuted and projected through the outlet duct by the flinger wheel.

5. In apparatus for the production of powders of low-melting-point metallic products, a comminuting unit comprising in combination a rotatable flinger wheel, and a substantially cylindrical casing therefor with an inlet for molten metal at the bottom and an outlet duct at the top, the lower part of said casing conforming with and being in close proximity to the periphery of said wheel for an angular measure of at least 180° , and being partially immersed in molten metal in a separate melting vessel so that metal flowing through said inlet is finely comminuted between the wheel and the casing.
